Atty.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed March 8, 1921. Serial No. 450,736.

To all whom it may concern:

Be it known that I, FRED S. CARR, a citizen of the United States, and a resident of Newton, in the county of Middlesex, 5 Commonwealth of Massachusetts, have invented an Improvement in Separable Fasteners, of which the following description, in connection with the accompanying drawings, is a specification, like characters on the drawings representing like parts.

This invention pertains to improvements in separable fasteners. It is among the objects of the invention to provide a superior fastener of inexpensive construction.

15 Referring to the drawings, which show a preferred form of one embodiment of my invention:—

Figure 1 is a front elevation of a fastener secured to its carrying fabric, the latter being broken away;

Fig. 2 is a section on the line 2—2 of Fig. 1;

Fig. 3 is a section on the line 3—3 of Fig. 2; and

25 Fig. 4 is a diagrammatic view illustrating the attachment of a stud to its carrying fabric.

Referring to the drawings and to the preferred form of my invention selected 30 for illustrative purposes, I have shown a stud having a head 5, a neck 6 and a base flange 7, which is preferably secured to the stud-carrying fabric 8 by prongs 9 penetrating the fabric and flanged over within a 35 stud-securing ring 10 providing interiorly an anvil or prong-turning surface 11. Where the preferred form of stud-securing means illustrated is used, the securing operation may be effected, as best shown in Fig. 4, 40 by a die 12 pressing against the base of the stud and a die 13 back-supporting the stud-securing ring 10, the prongs 9 being bent inwardly by the anvil portion 11 as the dies are pressed towards one another.

45 The preferred form of socket illustrated includes a casing 20 containing a spring 21, best shown in Fig. 3. This spring 21 may be flat and formed of any suitable spring metal, such as brass, formed to provide a 50 stud-receiving aperture 22 and split to provide resiliency. The preferred form of spring illustrated is split at 23 from the stud-receiving aperture 22 to the periphery of the spring and is provided at 24 with a 55 preferably arcuate cut-away portion into

which the slit 25 extends. Slit 25 is preferably in alignment with slit 23, as shown, and may be regarded as a continuation of the same. The stud-receiving aperture 22 may have lateral notches oppositely disposed 60 26 and 27, into which the neck of the stud may enter somewhat but not sufficiently to become locked therein against desired separation by relative tipping of stud and socket. The spring 21 may be notched peripherally at 28 and 29 and the casing 20 may be provided with abutments or projections 30 and 31 entering these notches, but providing sufficient clearance to permit opening of the spring to receive the head of the 70 stud. The notches 28, 29 and projections 30, 31 are for the purpose of preventing axial turning of spring 21 within its casing. It will be observed that in the preferred form of the invention the line of slits 23 75 and 25 is substantially at right angles to the line joining notches 29 and 30.

The preferred form of spring and casing heretofore described is peculiarly well adapted to resist undesired separation when 80 under lateral strain. When lateral strain is exerted toward either of the notches 26, 27, the neck of the stud partially enters therein, so that separation will not be readily effected by the resolution of forces tending to produce relative tipping between stud and socket. On the other hand, the stud and socket may be separated by a tipping strain at a somewhat greater angle than that produced by the resolution of forces arising from 85 lateral strain. Under strain in the directions heretofore mentioned in which the neck of the stud tends to enter one or the other of the notches 26, 27, the spring will be supported by the casing before sufficient 90 movement has taken place between spring and casing to bring the neck of the stud into contact with the casing.

Where strain is exerted in a direction either generally to the right or left of the 100 socket as viewed in Fig. 3, one side or the other of the notches 28 and 29 will engage the abutments or projections 30 and 31 on the casing, this engagement tending to press the opposite sides of the spring together 105 and thereby to oppose stud-releasing opening thereof.

While the socket containing the spring may be varied for different purposes, I may 110 conveniently secure it to the socket-carrying

fabric 40 by metallic securing means, and where this is the case the spring may be held in the casing by a spring-retaining plate 41 through which prongs 42 project, 5 said prongs 42 adapted to penetrate the fabric 40 and to be flanged over and engage in a socket-securing ring 43 on the opposite side of the stud-carrying fabric 40 from the socket casing. The attachment of the socket 10 to the fabric may be generally similar to the attachment of the stud to its carrying fabric hereinbefore described.

While I have shown and described a preferred form of one embodiment of my invention, it will be understood that major 15 changes involving omission, substitution, alteration and reversal of parts, and even changes in the mode of operation, may be made without departing from the scope of 20 my invention, which is best defined in the following claims.

Claims:

1. A separable fastener comprising, in combination, a stud having a head and a 25 neck, and a socket including a casing and a flat sheet metal spring in the casing, said spring having a stud-receiving aperture and lateral peripheral notches and projections from the casing entering said notches.
2. A separable fastener comprising, in combination, a stud having a head and a neck, and a socket including a casing and a spring in the casing, said spring having a stud-receiving aperture and lateral peripheral notches and projections from the casing 35 entering said notches, said spring having a slit extending generally in a direction transverse to a line between said notches.
3. A separable fastener comprising, in combination, a stud having a head and a neck, and a socket including a casing and a spring in the casing, said spring having a stud-receiving aperture and lateral peripheral notches and projections from the casing 45 entering said notches, said spring having a slit extending generally in a direction transverse to a line between said notches, said slit extending on opposite sides of the stud-receiving aperture in said spring.
4. A separable fastener comprising, in

combination, a stud having a head and a neck, and a socket including a casing and a spring in the casing, said spring having a stud-receiving aperture, a cut-away portion at one side of said aperture and a slit connecting said aperture with said cut-away portion. 55

5. A separable fastener comprising, in combination, a stud having a head and a neck, and a socket including a casing and a spring in the casing, said spring having a stud-receiving aperture, a cut-away portion at one side of said aperture and a slit connecting said aperture with said cut-away portion, and a second slit between said stud-receiving aperture and the periphery of the spring. 60

6. A separable fastener comprising, in combination, a stud having a head and a neck, and a socket including a casing and a spring in the casing, said spring having a stud-receiving aperture, a cut-away portion at one side of said aperture and a slit connecting said aperture with said cut-away portion, said cut-away portion arcuate in 70 form.

7. The combination of a separable fastener member having prongs projecting therefrom and a ringlike securing part for application to the opposite side of the fabric from 80 said member and providing an anvil surface inclined to bend said prongs inwardly and a clenching surface adjacent said fabric against which said prongs bear when clenched. 85

8. A socket for separable fasteners comprising, in combination, a casing, a flat spring in said casing, a spring-retaining plate, prongs extending from said casing through said spring-retaining plate, 90 said casing providing an offset portion for spacing said retaining plate from said spring and prong-engaging means on the opposite side of the socket-carrying fabric for engaging, turning and concealing 95 said prongs.

In testimony whereof, I have signed my name to this specification.

FRED S. CARR.
